(57) **CLAIM**

The ornamental design for a shelf divider, as shown and described.

DESCRIPTION

FIG. 1 is a front perspective view of a first embodiment of the shelf divider;

FIG. 2 is a left side view thereof;

FIG. 3 is a right side view thereof;

FIG. 4 is a front plan view thereof;

FIG. 5 is a rear plan view thereof;

FIG. 6 is a top plan view thereof;

FIG. 7 is a bottom plan view thereof;

FIG. 8 is a front perspective view of a second embodiment of the shelf divider;

FIG. 9 is a left side view thereof;

FIG. 10 is a right side view thereof;

FIG. 11 is a front plan view thereof;

FIG. 12 is a rear plan view thereof;

FIG. 13 is a top plan view thereof; and,

FIG. 14 is a bottom plan view thereof.

The broken lines showing is included for the purpose of illustrating environment of the article and forms no part of the claimed design.
